UNITED STATES PATENT OFFICE.

FREDERICK W. MIDGLEY, OF JERSEY CITY, NEW JERSEY, ASSIGNOR TO INTERNATIONAL TELEGRAPH CONSTRUCTION COMPANY, A CORPORATION OF NEW YORK.

TRANSMITTING APPARATUS.

974,169.

Specification of Letters Patent.

Patented Nov. 1, 1910.

Application filed February 1, 1906. Serial No. 298,897.

To all whom it may concern:

Be it known that I, FREDERICK W. MIDGLEY, a citizen of the United States, residing at Jersey City, in the county of Hudson and

5 State of New Jersey, have invented a new and useful Transmitting Apparatus, of which the following is a specification.

My invention relates to signaling systems in which the message or signal is represented during transmission by electro-radiant energy, and resides particularly in the transmitting apparatus for impressing such electro-radiant energy upon the natural media.

10 15 It is the object of my invention to provide transmitting apparatus which with a given input of electrical energy will radiate a maximum amount of electro-radiant energy, whereby receivers at very distant stations may be affected.

For an illustration of some of the forms my invention may take reference is to be had to the accompanying drawing, in which:—

20 25 Figure 1 is a diagrammatic view of transmitting circuits involving a looped aerial conductor with a condenser connected at the base of one leg of the loop. Fig. 2 is similar to Fig. 1 except that an oscillation transformer is employed to impress the high frequency oscillations upon the looped conductor. Fig. 3 is a diagrammatic view illustrating a further modification.

30 35 Referring to Fig. 1, A represents a looped aerial conductor comprising the legs a, a'. Between the leg a and the earth connection E is connected the variable inductance L, in shunt to a variable portion of which, through the rider r are serially connected the spark gap g and the condenser K. Connected across the spark gap g is the secondary S of a step up transformer whose primary is shown at P and includes a source G of alternating current or other suitable 40 45 source of interrupted current, and the operator's key k. At the base of the other leg a' is connected the condenser C, which is preferably variable or adjustable.

In Fig. 2, the secondary s of an oscillation transformer replaces the inductance L of Fig. 1. The primary of the oscillation transformer is shown at p, and different amounts of it, adjustable by the riders r, r'

55 are included in series with the spark gap g and the condenser K. As in Fig. 1 the secondary of a step up transformer bridges the spark gap G.

In Fig. 3 the condensers K and K' (or simply one condenser) are connected between the leg a and the earth E. In shunt to them is connected the inductance L, variable by the rider r, serially connected with the spark gap g. As in Fig. 1 the secondary S of a step up transformer bridges the gap. In the leg a', however, are serially connected 60 65 the adjustable condenser C and the inductance L', the latter variable by the rider r'. These dispositions of transmitting circuits are very effective indeed, the condenser C in the leg a' rendering the transmitting apparatus highly efficient.

What I claim is:

1. In a wireless signaling system, transmitting apparatus comprising the combination of an aerial conductor connected at one 75 end to earth, means for impressing electrical energy upon said conductor, and a conductor connecting the top of said aerial conductor non-inductively to earth, and a condenser connected in said last named conductor approximate its earth end.

2. In a wireless signaling system, transmitting apparatus comprising the combination of a looped aerial conductor, means associated with one leg of said loop for impressing high frequency electrical energy 85 thereon, a second leg of said loop non-inductively connected at its top to said first leg and non-inductively connected to earth, and a condenser connected in the second leg 90 approximate its earth connection.

3. In a wireless signaling system, transmitting apparatus comprising the combination of a looped aerial conductor, a condenser connected in one leg of the loop 95 approximate the lower end thereof, the loop legs non-inductively connected at their tops, and the leg containing said condenser non-inductively connected to earth, and means for impressing oscillations upon the loop 100 associated with another leg of the loop.

4. In a wireless signaling system, transmitting apparatus comprising the combination of an aerial conductor, means for impressing oscillations upon said conductor, a 105 condenser, a non-inductive connection at the

top of said aerial conductor, said connection being non-inductive and extending to earth through said condenser.

5. In a wireless signaling system, apparatus for transmitting electrical waves of long period comprising the combination of a looped aerial conductor having its legs connected to earth, the legs being non-inductively connected together at their tops, 10 a condenser connected in one leg of said loop approximate its earth connection, said leg including said condenser being non-inductive, and an oscillator independent of said loop impressing electrical energy upon 15 a second leg of said loop.

6. In a wireless signaling system, transmitting apparatus comprising the combination of a looped aerial conductor, a leg of said loop being substantially non-inductive 20 from its top to earth, a condenser connected in said loop approximate the earth connection, an oscillating circuit independent of

said loop, and a frequency determining element of said oscillating circuit connected in a second leg of said loop.

25

7. In a wireless signaling system, transmitting apparatus comprising a looped aerial conductor having its legs non-inductively connected together at the top, one of said legs being substantially non-inductive from its top to earth, a condenser connected in said leg approximate the earth connection, means for producing oscillations outside of said loop, and an operative connection between said means and a second leg 30 35 only of said loop.

In testimony whereof I have hereunto affixed my signature in the presence of the two subscribing witnesses.

FRED'K W. MIDGLEY.

Witnesses:

KATHRYN O'BRIEN,
ALICE S. MARSH.
